ELEVATOR-CONVEYOR MECHANISM

Orville J. Borrowdale, Chicago, Ill.

Application March 16, 1953, Serial No. 342,577

15 Claims. (Cl. 198—103)

This invention relates to improvements in an elevator-conveyor and refers particularly to a device for conveying or elevating materials such as coal, limestone, ore or the like from one elevation to a higher elevation.

One of the important objects of the present invention resides in the provision of a device for elevating, in a continuous manner, materials such as coal, limestone, ore or the like where said materials are contained in a compartment or space which is more or less cramped and does not permit the use of conventional conveyors, hoists or the like.

Another important feature of the present invention resides in a conveyor-elevator which comprises a plurality of endlessly moving cells or buckets which may be filled at their lower path of travel and are emptied at their upper path of travel, means being contemplated for rapidly unloading said cells at their upper travel in a relatively short space of time permitting a rapid cyclic operation of the device.

A further important feature of the invention resides in the provision of means for inverting the cells or buckets during their travel, gates being provided for the prevention of premature leaking or dumping of the material being elevated, including means for periodically opening and closing said gates at predetermined points in the path of travel of the cell.

Although the present invention may be used in many other environments, it is particularly adapted for the unloading of ships wherein the cargo is contained in relatively cramped spaces and where it is most desirable to unload and release the ship in the shortest time possible from the time of its docking. The device comprising the present invention is ideally adaptable for this purpose since, in a portable form it may be lowered into the hold of a ship and the features of its construction are such that it can operate rapidly and continuously.

Other objects and advantages of the present invention will be apparent from the accompanying drawings and following detailed description.

In the drawings, Fig. 1 is a front elevational view of the elevator-conveyor comprising the present invention.

Fig. 2 is a side elevational view of the device.

Fig. 3 is a sectional view of the device taken on line 3—3 of Fig. 1.

Fig. 4 is an enlarged detailed top plan view of one of the cells or buckets.

Fig. 5 is a sectional view taken on line 5—5 of Fig. 4.

Fig. 6 is a sectional view taken on line 6—6 of Fig. 4.

Fig. 7 is a sectional view taken on line 7—7 of Fig. 5 looking in the direction of the arrows.

Fig. 8 is a sectional view taken on line 8—8 of Fig. 5, looking in the direction of the arrows.

Fig. 9 is an enlarged detailed top plan view of a modification wherein the cell or bucket covers open differently, showing the covers in completely open position.

Fig. 10 is a view similar to Fig. 9 showing the covers in closed position.

Fig. 11 is a sectional view taken on line 11—11 of Fig. 9.

Fig. 12 is a sectional view taken on line 12—12 of Fig. 11.

5 Referring in detail to the drawings, 1—1 indicate vertical frame members connected together at the front and rear by bottom frame members 2 and top frame members 3. The front and rear frame members are joined in spaced relationship by channel irons 4. At the upper 10 four corners of the framework thus formed loop members 5 are positioned to receive the hooks or chains of a crane or hoist whereby the framework, which carries the elevator-conveyor to be hereinafter more fully described, may be moved from place to place, as the situs of the 15 material to be carried demands.

An elevator-conveyor mechanism, designated generally by the reference numeral 6, is carried within the framework hereinbefore described, the elevator-conveyor mechanism moving within the framework in a substantially circular path. On the framework, described, a pair of spaced substantially circular outer race supports 7 are carried. The elevator-conveyor frame comprises essentially a pair of spaced inner race supports 8 held in spaced relationship by a plurality of cross members 9.

20 25 An outer circular race 10 is carried by each of the outer race supports 7 and an inner circular race 11 is carried by each of the inner race supports 8, rollers 12 being positioned between each pair of races 10 and 11, whereby the elevator-conveyor frame is rotatably carried by the stationary framework.

30 35 On the inner portion of the inner race support 8 on one side of the elevator-conveyor frame, a relatively large ring gear 13 is carried. A pair of driving gears 14 mesh with the ring gear to move the elevator-conveyor frame upon the rollers 12. The stationary framework, hereinbefore described comprises horizontal beams 15 and vertical supporting beams 16 upon which an electric driving motor 17 is positioned. A drive sprocket 18 is mounted upon the shaft of motor 17 around which 40 45 sprocket chain 19 is trained. A conventional speed reducer 20 is also mounted upon the beams 15 and the input shaft thereof carries a sprocket wheel 21 over which chain 19 is trained and whereby power is transmitted to the speed reducer. The speed reducer has output shaft 22 upon which pinion 23 is mounted, the pinion being in mesh with the two driving gears 14 which, in turn, mesh with ring gear 13. In this fashion the elevator-conveyor frame is driven in a circular path.

50 55 In view of the fact that one of the advantages of the present invention is its compactness whereby it may be disposed in cramped spaces, I have found that the main drive mechanism comprising the motor 17, the speed reducer 20 and the various gears may advantageously be positioned at the central portion of the elevator-conveyor frame, as shown. However, it is to be understood that, if desired, the main drive mechanism may be positioned in either of the upper or lower corners of the stationary framework and still be disposed within the confines of the stationary frame. Of course, if any of the latter positions be employed, the elevator-conveyor frame will be 60 driven through an external ring gear instead of the internal ring gear 13.

65 70 A plurality of cells or buckets 24 are carried upon the elevator-conveyor frame, said cells being circular in transverse cross-section and being positioned on the rotatable frame with their axes disposed radially. As many cells 24 may be employed upon the rotatable elevator-conveyor frame as desired and since all cells and their accompanying mechanisms are identical, for purpose of clarity of description only one will be described in detail.

Each cell has a closed bottom 25 and a shaft 26 extends through the center of the bottom, the shaft and bottom being relatively rotatable. A brace member 27 extends transversely across the elevator-conveyor frame and is secured at opposite ends thereto, the brace 27 being rigidly connected to, and supporting the shaft 26. A spider 28 having crossed arms 29 is rigidly mounted upon shaft 26, the arms 29 extending radially to the inner wall of the cell and each of said arms, at its end carries a vane 30 which extends upwardly along the inner wall of the cell. As will be hereinafter more fully described, during operation of the device, the cell rotates while the vanes 30 remain stationary relative thereto whereby the vanes and arms function to scrape the side wall and bottom of the cell and loosen and prevent adherence of material carried therein thereby facilitating dumping thereof.

The mouth of each cell 24 is open and is positioned within a top ring 31 carried by a top plate 32 which comprises a portion of the frame of the elevator-conveyor. A bearing ring 33 is carried upon the outer wall of the cell 24 adjacent its upper end portion and functions as a bearing surface or race whereby the upper portion of the cell is laterally and rotatably supported by circumferentially spaced rollers 34. Between adjacent cells upon the elevator-conveyor a triangular frame section is carried having side walls 35 and 36 upon which bearing brackets 37 and 38, respectively, are mounted, the bearing brackets 37 supporting rollers 34 upon one side of a cell 24 and the bearing brackets 38 supporting rollers 34 upon the opposite side of an adjacent cell.

A combination ring gear and bearing ring 39 is mounted upon each cell adjacent the bottom portion thereof, each member having teeth 40 upon a radially extending portion and a roller surface formed upon a radially restricted portion 41. A frame section is provided between adjacent cells having frame members 42 and 43 which carry, respectively, roller brackets 44 and 45 which, in turn, carry rollers 46 which ride upon opposite side portions of the rings 41 of adjacent cells 24. Thus, the bottom portion of each cell is laterally and rotatably supported.

Upon the radially extending portion of the member 39 which carries teeth 40, a shoulder 47 is formed. A plurality of circumferentially spaced rollers 48 (Fig. 8) are positioned beneath the shoulder 47 and function as thrust bearings for the cell. Each roller 48 is carried by a radially extending shaft 49 which is carried by a bracket 50 supported by frame members 51 carried on each side of the elevator conveyor frame.

In this fashion each of the cells 24 is rotatable about its axis while carried by the elevator-conveyor frame which also rotates, each cell being supported laterally by rollers 34 and 46 and being supported axially by the rollers 48.

A spur gear 52 meshes with the teeth 40 and functions to rotate each cell, the spur gear being mounted upon a shaft 53 journaled in bearings 54. A bevel gear 55 is formed integral with spur gear 52 and meshes with a companion bevel gear 56 mounted upon a shaft 57 which, in turn, is journaled in bearings 58 carried by a portion of the elevator conveyor frame. A spur gear 59 is also rigidly mounted upon shaft 57 and functions to drive the bevel gears 56 and 55, the spur gear 52 and, hence, rotates the cell 24. A ring gear 60 is carried upon the stationary frame of the machine and spur gear 59 meshes therewith and, hence, when the elevator-conveyor frame is driven by motor 17 the gear 59 is driven thereby rotating the cells 24.

The ring gear 60 may be continuous throughout the circular path of travel of the cells in which case the cells may be continuously rotated throughout their entire travel or, if desired, the gear may be blanked, that is, devoid of teeth at predetermined portions of its circumference in which case the cells may be rotated inter-

mittently throughout the travel of the elevator-conveyor frame. For instance, depending upon the nature of the material carried it may be desirable to have the cells rotate continuously so that the arm 29 and vanes 30 may keep the cells clean, whereas with other material it may be desired to rotate the cells only for a predetermined portion of their travel, for instance, just before the material is dumped therefrom. If intermittent rotation of the cells about their axes is desired, suitable clutch mechanism (not shown) associated with each cell may be employed, instead of the blanked ring gear, which may be periodically actuated during predetermined portions of the travel of the cells.

In employing the present invention, a feed conveyor 61 and a discharge conveyor 62 are employed to respectively feed material to the lower portion of the elevator conveyor and discharge the material at the upper portion of the device, the elevator-conveyor functioning primarily as an elevating connection between the two conveyors.

The feed conveyor 61 may be of conventional construction, and for purposes of illustration an endless belt 63 may be employed which at each end may be trained around a roll 64 (only one of which is shown). The belt 63 may be supported and guided by suitable rollers 64 and for purposes of guiding and confining the material carried by the upper pass of the conveyor a hood or trough may be employed, the hood, at its discharge end terminating in a nozzle or funnel 66 which opens over the mouth of a cell when it occupies its lowermost position in its path of travel.

The discharge conveyor 62 may also be of conventional construction and may comprise an endless belt supported by rollers 68 and trained around end rolls 69 (only one of which is shown). A trough or hood 70 may be employed to confine the material carried on the upper pass of the belt. The feed end of the discharge conveyor 62 may be positioned beneath the path of travel of the cells 24 at the uppermost portion of travel thereof and the trough walls 71 may flare outwardly to embrace a portion of the arc of travel of the cells equal to the span of two cells, that is, one complete central cell and the halves of the two adjacent cells, as shown best in Fig. 1.

It will be noted that, as the elevator-conveyor is rotated, as indicated by arrow 72 in Fig. 1, the cells at the top portion of the elevator are inverted. In order to prevent the material carried by the cells from being spilled or dumped therefrom prematurely, that is, before the cell comes within the span of the trough 71, covers are provided for each cell which are opened and closed during predetermined portions of travel of the elevator-conveyor.

A gate guide 73 is mounted upon the top plate 32, said guide being circular in conformity to the cell section. Each guide carries an annular rib 74 which partitions two annular grooves 74 and 75 for the reception of the edges of, respectively, an upper substantially circular cover plate 76 and a lower substantially circular cover plate 77. Each of the cover plates is provided with a substantially semi-circular aperture 76' and 77' one above the other when the cell mouth is open or may be positioned to stagger apertures 76' and 77' when the cell mouth is closed. The covers are moved automatically in a manner and by means hereinafter more fully described.

On each side of the elevator-conveyor frame adjacent each cell is a vertical shaft 78 and 79, and each shaft is journaled in bearings 80, a pair of which are disposed on each side of the cell and are mounted upon frame members carried by the elevator-conveyor. Shafts 78 and 79 are disposed parallel to the axis of an adjacent cell and respectively carry at their ends spur gears 81 and 82. The gate guide 73 is provided with an aperture 83 adjacent each gear 81 and 82 and the circular portions of each of the gates 76 and 77 carry teeth 84, the ar-

angement being such that gear 82 meshes with the teeth of gate 76, the outer gate, including the teeth on the ring portion thereof which defines aperture 76', and gear 81 meshes with the teeth of gate 77, the inner gate, including the teeth upon the ring portion of the gate which defines aperture 77'. Thus, rotation of gear 82 moves the outer gate 76 and rotation of gear 81 moves the inner gate 77.

A shaft 85 and 86 is positioned upon each side of a cell 24 and the ends of said shafts are respectively connected by universal grants 87 (only one of which is shown) to the ends of shafts 78 and 79. The shafts 85 and 86 are disposed radially with respect to the movement of the elevator-conveyor and each carries at its end a spur gear 88 and 89, respectively, which are adapted to mesh with gear segments disposed adjacent the path of travel of the elevator-conveyor, to be hereinafter more fully described.

In the operation of the machine, the stationary frame, carrying the elevator-conveyor, is positioned at the situs of use, for instance, the hold of a ship. The conveyor 61 also of a portable nature would, in the example set forth, extend lengthwise of the ship's hold and would function to carry cargo material to the elevator conveyor on the upper pass of the belt 63. The material thus conveyed is dumped into a cell 24, the gates of which are in open position, that is, the apertures 76' and 77' are in substantial coincidence and are each on the side of the cell adjacent the trough 66 of the conveyor 61. The elevator-conveyor moves continuously and the movement of the conveyor belt 63 will be correlated to the rotary movement of the elevator-conveyor so as to substantially completely fill the cell as the cell passes the trough 66.

Referring particularly to Fig. 1, shortly after the lowermost cell 24 leaves its lowermost position, the gear 88 encounters a segment 90 which is carried by the stationary frame, and continued movement of the elevator-conveyor results in a half turn of the upper gate 76. Thus, the mouth of the cell 24 is closed and unintended spilling of the contents of the bucket will be prevented as the elevator-conveyor continues its rotation carrying the cell, in question, upwardly. As the movement of the elevator-conveyor continues, both gears 88 and 89 encounter segmental gears 91 and 92 (Fig. 2) which are disposed on the stationary frame in the path of travel of said gears. The segmental gears 91 and 92 are shorter arcuately than segmental gear 90 and during meshing of the respective gears 88 and 89 with said segments, each of the gates 76 and 77 moves a quarter turn. It will be noted that the segmental gears 91 and 92 are disposed in advance of the position of the trough 71 whereby said gates begin opening as soon as the leading side of the cell comes into radial alignment with the trough and the initial opening of the gates occurs at the advancing side of the gates. Thus, before the entire cell mouth is over the trough 71, the openings 76' and 77' are in coincidence, but each of the gates is disposed at right-angles to the position they occupied at their lowermost position on the elevator-conveyor.

The time of discharge is, of course, an important factor in a device of this type, since it is an important factor in the rate of rotation of the elevator-conveyor, which, in turn, determines the capacity of the machine. The time of discharge, in turn, depends upon the arc length spanned by the trough 71, and, hence, by opening the gates in the manner described the greatest advantage can be taken of the arc length of the troughs.

After the material has been dumped from the cell, in question, it is caught by the upper pass of the belt 67 and conveyed forwardly to a desired situs. As the cell, in question, continues its movement, the gears 88 and 89 encounter another pair of segmental gears 93 similar to the gears 91 and 92 whereby the gates 76 and 77 are

given a quarter turn to bring them to the loading position hereinbefore described.

Of course, as has been hereinbefore described, the individual cells 24, during their travel with the elevator-conveyor, will be rotated continuously or intermittently about their own axes which tends to loosen the material conveyed and condition it for rapid dumping and also to maintain the cell walls clean.

In the event that the discharge conveyor stops or if for any other reason it is desired to stop the movement of the elevator conveyor occasioned by its momentum, a brake upon the elevator conveyor is contemplated. The brake comprises a pair of brake shoes 94 and 95, each of which is carried on a pivot 96, at its lower end, the shoes being arcuate and being adapted to bear against a brake ring 97 carried upon the stationary frame. A link 98 is pivotally connected to the shoe 94 and a link 99 is similarly pivoted to the shoe 95. At their opposite ends each of the links 98 and 99 are pivoted to a master link 100 an end of which is pivotally connected to piston rod 101 which operates in a hydraulic cylinder 102. The cylinder 102 receives fluid under pressure from a suitable source (not shown) whereby the brake may be applied when occasion demands.

Referring particularly to Figs. 9, 10, 11 and 12 a modification of the present invention is shown, the modification relating particularly to the cell gates and the manner of opening and closing the same. In this form of the invention the device has a stationary frame and a rotatable elevator-conveyor frame similar to the one hereinbefore described, except that the elevator conveyor frame is wider. The elevator conveyor carries cells which are loaded by a conveyor similar to the conveyor 61 hereinbefore described and unload upon a conveyor, such as conveyor 62.

Referring particularly to Fig. 12, the stationary frame comprises outer race supports 103 and the elevator conveyor comprises inner race supports 104, the same being respectively similar to the outer and inner race supports 7 and 8 hereinbefore described. An outer race 105 is carried by the outer race support 103 and an inner race 106 is carried by the inner race support 104. Rollers 107 are positioned between the outer race and inner race whereby the elevator-conveyor frame is rotatably positioned upon the stationary frame. The elevator conveyor is driven, as hereinbefore described, by suitable driving means such as, motor 17, speed reducer 20, gears 14 and ring gear 13.

The elevator conveyor frame carries a plurality of cells or buckets 108 and inasmuch as each of the cells and the operating mechanisms for the cells and the gates which cover the mouths of the cells are the same, only one of the cells and the operating mechanisms appurtenant thereto will be described.

Mounted upon a portion 109 of the elevator conveyor frame is a channel member 110 which is connected at its opposite ends to the frame members 109. Intermediate the length of the channel member 110 a shaft 111 is rigidly positioned, said shaft extending upwardly through the bottom of cell 108, the cell being rotatable relative to said shaft. A spider having a plurality of radially extending arms 112 is rigidly carried upon shaft 111 within the cell 108, said arms extending along the bottom of the cell and terminating adjacent the lateral wall of the cell. Each of the arms 112 carries an upwardly extending vane 113 which is disposed adjacent the inner surface of the lateral wall of the cell 108. In operation, the cell is rotated whereas the arms 112 and vanes 113 remain stationary whereby the material carried in the cell is agitated by the arms and the vanes and the defining walls of the cell are maintained clean. This, as has been hereinbefore described, facilitates the unloading of the cell particularly where material is carried in the cell which has a tendency to cake or adhere to the walls of the cell.

A bearing ring 114 is positioned upon the outer wall

of the cell 108 adjacent its upper end and a ring member 115 is similarly positioned adjacent the lower end portion of the cell. The ring member 115 has a radially projecting portion 116 which carries gear teeth 117 at its periphery. Formed integral with the radially extending portion 116 is a bearing portion 118 which is positioned beneath the radially extending portion 116.

Frame members 119 and 120 carried by the elevator conveyor frame are positioned upon opposite sides of each cell, the frame member 120 carrying a roller bracket 121 which supports a rotatable roller 122. The frame member 119 carries a roller bracket 123 which in turn carries a roller 124. There are two pairs of roller brackets 121 upon the frame member 120 which permit rollers 122 carried by said brackets to bear upon the bearing ring 114 at one side of the cell. At the opposite side of the cell 4 roller brackets 123 supporting rollers 124 permit said rollers to bear upon the bearing ring 114 carried by the cell. In this fashion, the cell 108 is laterally supported during its rotation about its axis.

A frame member 125 also carried by the elevator conveyor frame carries a pair of roller brackets 126, each of which support a roller 127. Adjacent the frame member 125 a second frame member 128 carries a pair of roller brackets 129 each of which carries a roller 130. As has been hereinbefore described in conjunction with the rollers 122 and 124, the rollers 127 and 130 bear upon the ring 118 whereby the lower portion of the cell is laterally supported during its rotation about its axis. As has been hereinbefore described in conjunction with cell 24 rollers 131, similar to the rollers 148 function as thrust bearings for the cell 108, said rollers engaging the lower face of the radially extending portion 116. In this fashion the cell 108 is rotatably supported in an axial direction.

A pair of space bearings 132 support a shaft 133 which in turn carries spur gear 134, said spur gear meshing with the teeth 117 upon the bearing member 115. A bevel gear 135, which may be formed integral with the spur gear 134 is also mounted upon shaft 133. Bevel gear 135 meshes with a companion gear 136 carried upon a shaft 137, said shaft also carrying a spur gear (not shown) which meshes with a ring gear carried by the stationary frame, the arrangement being similar to the relationship between spur gear 59 and ring gear 60, hereinbefore described.

The arrangement is such that as the elevator conveyor frame rotates upon the stationary frame the shaft 137 is rotated which in turn rotates shaft 133 and hence each of the cells 108 is rotated about its axis. As has been hereinbefore described in conjunction with the rotation of the cells 24, the cells 108 may be continuously rotated during the rotation of the elevator conveyor or said cells may be intermittently rotated by blanking portions of the ring gear which is similar to the gear 60 hereinbefore described. In other words, the operation of the cell 108 is identical with the operation of the cell 24 so far as its rotation is concerned.

Each of the cells 108 is open at one end and each is rotatably positioned within a ring 138, carried by a circular flange 139, in turn, carried by a plate 140 comprising a portion of the elevator-conveyor frame, the flange 139 circumscribing the cell 108 adjacent its open mouth. A gate member 141 is slidably positioned upon the plate and comprises a half gate for closing the mouth of the cell 108. A second gate member 142 is slidably positioned in a plane parallel relationship to and above the gate member 141 and comprises the other half gate which together with gate member 141 effects a complete closure for the cell mouth. Gate member 142 is supported at its opposite edges by ribs 143 carried by frame members 144, a cover frame member 145 being positioned above the frame members 144. The arrangement is such that plate 140, ribs 143 and cover frame member 145 provide spaced parallel grooves in which the gate members 141 and 142 may slide transversely of the elevator-

conveyor frame to completely close or completely expose the mouth of the cell.

Each of the gate members or half gates 141 and 142 are rectangular in shape and carry gear teeth on each of their opposite edges, the gear teeth on gate member 141 being designated 146 and the gear teeth on gate member 142 being designated 147. In effect the gear teeth 146 and 147 form racks and the teeth 146 on each side of gate member 141 engage with pinions 148, gear teeth 147 on each side of gate member 142 meshing with opposite pinions 149. By rotating pinions 148 and 149 the gate members 141 may be opened or closed, said gate members when in closed position overlapping at the center of the cell mouth.

A shaft 150 is rotatably mounted in bearings 151 and 152 carried by channel iron 10 and bearing bracket 153, respectively, the latter being mounted upon plate 140. Within bracket 153 shaft 150 carries a bevel gear 154 which meshes with a companion bevel gear 155 carried upon a shaft 156 which is journaled in bearing 157 mounted upon bracket 153 and bearings 158 mounted upon depending frame members 159. A spiral gear 160 is mounted upon each end of shaft 156 and each gear meshes with companion spiral gears 161 mounted upon shafts 162. The pinions 148 which mesh with the teeth 146 upon the opposite side of gate member 141 are mounted upon shafts 162 and are rotated thereby to move the gate member, as will be hereinafter more fully described.

On the opposite side of the cell 108 a shaft 163 is journaled in bearings 164 and 165 carried by channel 110 and frame member 165, respectively, the latter being suspended from plate 140. Within bracket 165 shaft 163 carries a bevel gear 166 which meshes with bevel gear 167 carried upon a shaft 168 which is journaled in bearing 169 mounted upon bracket 165 and bearings 170 carried by frame members 171. A spiral gear 172 is carried at each end of shaft 168 and each gear meshes with a companion spiral gear 173, the gears 173 being mounted upon shafts 174, the shafts which carry pinions 149 for moving gate 142.

In the operation of the modified gates 141 and 142, when a cell 108 is at its lowermost position on the elevator conveyor the gates 141 and 142 will be open, that is, the gates will be in the position shown in Fig. 9. The cell is then loaded by the conveyor 61 and as the cell moves from the lowermost position the gates are closed, as shown in Fig. 10. When the cell reaches the nearest side of the trough 71 the gates 141 and 142 are again opened and the material is dumped therefrom to the conveyor 62, the gates remaining open until the cell again moves from its lowermost position, as described.

To open and close the gates 141 and 142, as described, a pinion 175 is carried at the lower end of shaft 150 and a pinion 176 is mounted upon the lower end of shaft 163. Adjacent the paths of travel of the pinions 175 and 176 and carried on the stationary frame, a pair of racks (not shown) are positioned so as to be contacted by said pinions immediately after the cell, associated with said pinions, has been filled. The pinions 175 and 176 are thus rotated and in order that they be rotated oppositely to move the gate members 140 and 142 oppositely, the racks are so disposed as to contact opposite sides of the pinions, that is, one rack contacts one side of pinion 175 while the second rack simultaneously contacts the opposite side of pinion 176. In this fashion the gate members close. When the cell 108 moves completely over the trough 71 a pair of racks, similar to those described, again contact pinions 175 and 176, to open the gate members 141 and 142 to permit unloading of the cells.

In view of the fact that the gates contemplated in the form of the invention shown in Figs. 9, 10, 11 and 12 completely expose the mouth of the cells as opposed to the form shown in the remaining figures, wherein the cell mouth is only about half opened, the time necessary

to dump the cell load in the trough 71 is shorter and, hence, it is permissible to open gate members 141 and 142 at a later phase of the elevator-conveyor travel adjacent the conveyor 62 than was the case in the opening of the gates 76 and 77.

It is apparent that herein is provided an elevator-conveyor which occupies a relatively small space; is portable, and can be rotated rapidly, and can be readily timed with two horizontal parallel conveyors at different elevations to rapidly convey material from a lower to an upper level.

I claim as my invention:

1. An elevating and conveying device comprising a relatively stationary frame, a rotatable frame mounted upon said stationary frame, means for rotating said rotatable frame, a plurality of open mouthed cells carried by said rotatable frame for the reception of material to be elevated and conveyed, gates upon each of said cells and slidably movable across the mouths of said cells for closing the mouths of said cells, gate-moving means connected to each of said gates for slidably moving said gates to open and close the gates of each cell, and means carried by said relatively stationary frame at predetermined positions adjacent the path of travel of said cells to actuate said gate-moving means when said rotatable frame moves.

2. An elevating and conveying device comprising a relatively stationary frame, a rotatable frame mounted upon said stationary frame, means for rotating said rotatable frame, a plurality of open mouthed cells carried by said rotatable frame for the reception of material to be elevated and conveyed, gates upon each of said cells for closing the mouths of said cells, gate-moving means connected to each of said gates for opening and closing the gates of each cell, said gate-moving means comprising a gear, and gear means carried by said relatively stationary frame at predetermined positions adjacent the path of travel of the gears of the gate-moving means to engage said gears and actuate said gate-moving means when said rotatable frame moves.

3. An elevating and conveying device comprising in combination, a relatively stationary frame, a rotatable frame mounted upon said stationary frame, means for rotating said rotatable frame in a vertical plane, a plurality of circular-sectioned open-mouthed cells carried by said rotatable frame for the reception of material to be elevated and conveyed, vanes rigidly connected to said rotatable frame and carried within each cell adjacent the inner wall of the cell, means carried by said stationary frame for rotating each cell about its axis when said rotatable frame moves whereby to agitate the material in the cell, gates upon each of said cells for closing the mouths of said cells, gate-moving means connected to each of said gates for opening and closing the gates of said cells, and means carried by said stationary frame at predetermined positions adjacent the path of travel of said cells to actuate said gate-moving means when said rotatable frame moves.

4. An elevating and conveying device comprising a relatively stationary frame, a rotatable frame mounted upon said stationary frame, means for rotating said rotatable frame, a plurality of open mouthed cells carried by said rotatable frame for the reception of material to be elevated and conveyed, gates movably carried in plane-parallel slidable relationship to the mouth of each cell for closing the mouths of said cells, gate-moving means carried by each of said cells for slidably opening and closing the gates of each cell, and means carried by said relatively stationary frame at predetermined positions adjacent the path of travel of said cells to actuate said gate-moving means when said rotatable frame rotates.

5. An elevating and conveying device comprising in combination, a relatively stationary frame, a rotatable frame mounted upon said stationary frame for rotation in a vertical plane, means for rotating said rotatable frame, a plurality of open-mouthed cells carried by said

rotatable frame with said open mouths facing the center of rotation of said rotatable frame and with the axes of said cells disposed substantially radially, means for feeding material to be elevated and conveyed to said cells at their lowermost position upon said rotatable frame, gates upon each of said cells for closing the mouths of said cells, gate-moving means connected to each of said gates for moving said gates at right-angles to open and close the gates of each cell, means positioned at the upper portion of travel of said cells on said rotatable frame for receiving elevated material from said cells, means carried by said relatively stationary frame for actuating said gate moving means to close and open said gates respectively adjacent said loading and unloading positions of said cells during rotation of the rotatable frame.

6. An elevating and conveying device comprising in combination, a relatively stationary frame, an annular rotatable frame mounted upon said stationary frame for rotation in a vertical plane, means for rotating said rotatable frame, a plurality of open-mouthed cells carried by said rotatable frame with said open mouths facing the center of rotation of said rotatable frame, means positioned at a loading station within said annular frame above the lowermost position of said cells on said rotatable frame for feeding material to said cells, means carried by said stationary frame adjacent said loading station for closing the mouths of said cells after they pass from the loading station, means positioned at an unloading station within said annular frame beneath the uppermost position of the cells on said rotatable frame for receiving material discharged from said cells, and means carried by said stationary frame adjacent said unloading station for opening the mouths of said cells before they pass to said unloading station.

7. An elevating and conveying device comprising in combination, a relatively stationary frame, an annular rotatable frame mounted upon said stationary frame for rotation in a vertical plane, means for rotating said rotatable frame, a plurality of open-mouthed cells carried by said rotatable frame with said open mouths facing the center of rotation of said rotatable frame, means positioned at a loading station within said annular frame above the lowermost position of said cells on said rotatable frame for feeding material to said cells, means for closing the mouths of said cells after they pass from the loading station, means positioned at an unloading station within said annular frame beneath the uppermost position of the cells on said rotatable frame for receiving material discharged from said cells, means for opening the mouths of said cells before they pass to said unloading station, and means for rotating each cell a predetermined degree about its axis during its passage from the loading station to the unloading station.

8. An elevating and conveying device comprising in combination, a relatively stationary frame, an annular rotatable frame mounted upon said stationary frame for rotation in a vertical plane, means for rotating said rotatable frame, a plurality of open-mouthed cells carried by said rotatable frame with said open mouths facing the center of rotation of said rotatable frame, means positioned at a loading station within said annular frame above the lowermost position of said cells on said rotatable frame for feeding material to said cells, means for closing the mouths of said cells after they pass from the loading station, means positioned at an unloading station within said annular frame beneath the uppermost position of the cells on said rotatable frame for receiving material discharged from said cells, scraping means carried rigidly with said rotatable frame and positioned within each cell, and means for rotating each cell about its axis on said stationary frame during its passage from the loading station to the unloading station.

9. An elevating and conveying device comprising a relatively stationary frame, a rotatable frame mounted upon said stationary frame, means for rotating said ro-

tatable frame, a plurality of open mouthed cells carried by said rotatable frame for the reception of material to be elevated and conveyed, gates upon each of said cells and movable slidably over the mouths of said cells for closing the mouths of said cells, gate-moving means connected to each of said gates for slidably moving said gates over the mouths of said cells to open and close the gates of each cell, means carried by said relatively stationary frame at predetermined positions adjacent the path of travel of said cells with said rotatable frame to actuate said gate-moving means, and brake means carried by said stationary frame for retarding movement of said rotatable frame.

10. An elevating and conveying device comprising in combination, a relatively stationary frame, a rotatable frame mounted upon said stationary frame, means for rotating said rotatable frame in a vertical plane, a plurality of circular-sectioned open-mouthed cells carried by said rotatable frame for the reception of material to be elevated and conveyed, a pair of substantially semi-circular gates carried by said rotatable frame and disposed in plane-parallel over the mouth of each cell, and means for rotating said gates to superimpose said gates to open said cell mouth and offset said gates to close said cell mouth during rotation of said rotatable frame.

11. An elevating and conveying device comprising in combination, a relatively stationary frame, a rotatable frame mounted upon said stationary frame, means for rotating said rotatable frame in a vertical plane, a plurality of circular-sectioned open-mouthed cells carried by said rotatable frame for the reception of material to be elevated and conveyed, a substantially circular guide frame mounted on said rotatable frame and disposed adjacent the mouth of each cell, said guide frame being provided with a pair of annular gate grooves, a substantially semi-circular gate slidably disposed in each groove, and means for rotating said gates relative to each other to superimpose said gates to open the cell mouth and offset said gates to close said cell mouth during rotation of said rotatable frame.

12. An elevating and conveying device comprising in combination, a relatively stationary frame, a rotatable frame mounted upon said stationary frame, means for rotating said rotatable frame in a vertical plane, a plurality of circular-sectioned open-mouthed cells carried by said rotatable frame for the reception of material to be elevated and conveyed, a substantially circular guide frame mounted on said rotatable frame and disposed adjacent the mouth of each cell, said guide frame being provided with a pair of annular gate grooves, a substantially semi-circular gate slidably disposed in each groove, teeth carried on the arcuate edges of each gate, a pair of gears carried by said rotatable frame and meshing with the teeth of said gates, and means carried upon said stationary frame at predetermined arcuate positions adjacent the path of travel of said rotatable frame for rotating said gears to superimpose and offset said gates for opening and closing the mouth of the cell.

13. An elevating and conveying device comprising a relatively stationary frame, a rotatable frame mounted upon said stationary frame, means for rotating said rotatable frame, a plurality of open mouthed cells carried by said rotatable frame for the reception of material to be elevated and conveyed, a pair of gates carried upon said rotatable frame adjacent the mouth of each cell, said gates being disposed in plane-parallel slidable position with respect to each other, and means for sliding said gates in opposite directions to cover opposite halves of said cell mouth to close said mouth and to uncover said opposite halves of said cell mouth to open said cell mouth during rotation of said rotatable frame.

14. An elevating and conveying device comprising a relatively stationary frame, a rotatable frame mounted upon said stationary frame, means for rotating said rotatable frame, a plurality of open mouthed cells carried by said rotatable frame for the reception of material to be elevated and conveyed, a pair of gates carried upon said rotatable frame adjacent the mouth of each cell, said gates being disposed in plane-parallel slidable position with respect to each other, and means for sliding said gates in opposite directions to cover opposite halves of said cell mouth to close said mouth and to uncover said opposite halves of said cell mouth to open said cell mouth during rotation of said rotatable frame, said means comprising gear teeth carried on opposite edges of each gate, gears carried by said rotatable frame which mesh with said gate gear teeth, and means carried by said stationary frame adjacent the path of travel of said cells for rotating said gears at predetermined positions of travel of said rotatable frame.

15. An elevating and conveying device comprising a relatively stationary frame, a rotatable frame mounted upon said stationary frame, means for rotating said rotatable frame, a plurality of open-mouthed substantially circular cells carried by said rotatable frame for the reception of material to be elevated and conveyed, gates carried by each of said cells for closing the mouths of said cells, gate-moving means carried by each of said cells for opening and closing the gates of each cell, means carried by said relatively stationary frame at predetermined positions adjacent the path of travel of said cells to actuate said gate-moving means, means for rotating said cells about their respective axes during rotation of said rotatable frame, and rollers carried by said rotatable frame for supporting said cells axially and laterally.
